(57) **CLAIM**

The ornamental design for a charger for a powered brush handle, as shown and described.

DESCRIPTION

FIG. 1 is a top front right perspective view of a charger for a powered brush handle in accordance with our new design; FIG. 2 is a front elevation view thereof; FIG. 3 is a rear elevation view thereof; FIG. 4 is a top plan view thereof; FIG. 5 is a bottom plan view thereof; FIG. 6 is a left side elevation view thereof; FIG. 7 is a right side elevation view thereof; and, FIG. 8 is a bottom rear right perspective view thereof. The broken lines shown in the drawings illustrate portions of the charger for a powered brush handle that form no part of the claimed design.

1 Claim, 6 Drawing Sheets
